David K. Morrison, Arlington, Va.

Application October 4, 1944, Serial No. 557,210

2 Claims. (Cl. 35—19)

(Granted under the act of March 3, 1883, as
amended April 30, 1928; 370 O. G. 757)

1

This invention relates to improvements in educational and training devices to be used in the training of electrical students and apprentices to construct electrical circuits, and to familiarize them with standard electrical symbols employed in wiring diagrams.

An object of the invention is to provide a simple and inexpensive device which will enable electrical students and apprentices to construct electrical circuits and to take different readings thereon after the circuit has been constructed in accordance with a wiring diagram.

Another object of the invention is to provide a device which teaches the construction of an electrical circuit by the sight method.

Various other objects and advantages will be apparent from the following description of the invention and the novel features will be particularly pointed out hereinafter in connection with the appended claims.

In the accompanying drawings:

Figure 1 is a perspective view of the invention wherein is shown a circuit partially constructed in accordance with a wiring diagram depicted on a template positioned upon the training device.

Figure 2 is a top plan view of the cabinet forming a part of the invention.

Figure 3 is a longitudinal sectional view taken on the line 3—3 of Figure 2.

Figures 4 and 5 are detail perspective views of two of the electrical circuit constructing units.

Referring to the drawings in detail and more particularly to Figure 1, the reference numeral 10 indicates generally our improved training device and comprises a shallow rectangular cabinet 11, a series of templates or lesson sheets 12 (one of which is illustrated in position upon the cabinet and others stored therein) and several interchangeable electrical circuit constructing units, namely, connectors, crossovers, switches, lamps and resistors 13—17, respectively, and as shown, the units 13, 14, 15 and 16 have been employed in partially constructing the circuit and the unit 17 along with others are stored within the cabinet.

The cabinet 11 comprises a top 18, a bottom 19, side rails 20 and 21, an end rail 22 and partitions 23, 24 and 25. The partitions 23, 24 and 25 divide the intervening space between the top 18, bottom 19, side rails 20 and 21 and the end rail 22 into compartments 26, 27 and 28. A drawer 29 is slidably fitted within the compartment 26 and provides ample storage space for the safekeeping of the aforementioned templates 12 when not in use. The top 18 of the cabinet 11 is cut away as at 30 and 31 immediately above the compart-

ments 27 and 28 to provide openings into which are fitted a detachable cover 32 and a panel 33 respectively. The detachable cover 32 permits access to the compartment 27 wherein are stored 5 the interchangeable electrical circuit constructing units 13—17 which will be more fully described in detail as the description proceeds. The panel 33 is of any suitable insulating material and has affixed thereto the necessary standard 10 electrical testing apparatus employed in testing and taking readings on electrical circuits. The circuit connecting the several elements of the testing apparatus is made on the undersurface of the panel 33, thereby confining the circuit 15 within the compartment 28 after the panel 33 has been secured in place and protects the same from becoming damaged or short circuited by tools or other implements inadvertently placed thereon; which would be the case should the circuit 20 be exposed.

To that portion of the top 18 between the cut out portions 30 and 31 are affixed a pair of bus bars B provided at their opposite ends with terminals T and T'. To the terminals T are attached the conductors leading from a source of 25 electrical current and to the terminals T' are attached conductors 13 completing the built up electrical circuit.

To the major portion A of the top 18 and arranged in equidistant rows are secured washers 34 by means of headed studs 35, the heads 36 of which project above the washers 34 and provide means to which are attached the interchangeable electrical circuit constructing units.

The templates 12 are provided with perforations 37 arranged for registration with and to snugly fit the washers 34, thereby permitting the heads 36 of the studs 35 to project therethrough and to frictionally hold the templates in place 35 upon the surface A of the top 18 of the cabinet. It should be clearly understood that each of the templates 12 making up a complete course in electrical wiring are perforated to correspond 40 with the arrangement of the studs 35, so that any one of such templates bearing different wiring diagrams may be applied to the top 18. As 45 illustrated in Figure 1, the template 12 has depicted thereon a wiring diagram 38 which, as shown, interconnects only certain of the perforations 37.

Referring now to the electrical circuit constructing units 13—17 which form an important part of our invention, the unit 13, here designated a conductor, simulates a wire or cable and is therefore employed as such in constructing a circuit in connection with the training device,

and comprises eyelets 12a, the inner ends of which are secured by welding, brazing or soldering to an intermediate resilient spring 13b. The presence of the resilient spring 13b intermediate the eyelets 12a of the conductor will maintain it under tension when it is slightly stretched for its eyelets to bridge the distance between adjacent studs 35. The unit 14, designated a cross-over conductor, is employed when it is desired to bridge one or more of the studs 35 and comprises eyelets 14a and a spring 14b, one of the eyelets 14a is of greater length than the other and is provided with a bowed portion 14c adapted to clear the stud over which the conductor passes. The unit 15, designated a switch, comprises eyelets 15a, spring 15b and a switch member 15c. The unit 16, designated a lamp, comprises eyelets 16a, spring 16b and an incandescent lamp 16c and the unit 17, designated a resistor, comprises eyelets 17a, spring 17b and a resistance coil 17c.

Operation

A template 12 bearing the desired wiring diagram is selected by the student from the series of templates and is positioned upon the surface A of the cabinet 11. The student now selects from the electrical units 13-17 the unit corresponding to the electrical symbol contained in the wiring diagram depicted between two adjacent studs 35 and applies the same thereto. This procedure is continued until the superposed electrical units completely obliterate the wiring diagram. The built up circuit is then connected to the terminals T' thereby completing the circuit to the source of electrical energy. With all switches contained in the circuit closed and providing the student has correctly followed instructions and his selection of electrical units is correct the incandescent lights 16 should glow.

As will be apparent from Figure 1 of the drawings, test leads are provided for obtaining indications from the meter M of the testing apparatus. The test leads, as shown, are applied across one of the incandescent lamps presumably to measure the voltage drop.

Thus far the invention has been described and illustrated as a device for training electrical students and apprentices in reading electrical wiring diagrams and to construct electrical circuits in accordance therewith. However, it will become apparent from the foregoing description when taken in conjunction with the drawings that the invention could be employed as a training device for children in teaching them to construct geometrical designs and to identify and match colors.

These and other variations of the invention will be apparent to those skilled in the art as falling within the scope of the invention as defined by the appended claims.

The invention described herein may be manufactured and used by or for the Government of the United States of America for governmental purposes without the payment of any royalties thereon or therefor.

What we claim is:

1. Portable electrical educational apparatus of the character disclosed comprising, in combination, thin rectangular frame means having a substantially flat upper face member composed of non-conducting material, a plurality of studs of conducting material affixed to said face member in equally spaced parallel rows, the distance between studs in a row being the same as the distance between rows, a plurality of washers for said plurality of studs respectively, a template

removably mounted upon said face member, said template having a plurality of openings therein corresponding in spacing to the disposition of the studs on said face member, said template being composed of non-conducting material, said openings being substantially similar in diameter to the washers whereby said washers snugly fit in said openings respectively and the template is prevented from substantial sliding movement on said face member, said template having means thereon forming an electrical circuit diagram, a plurality of circuit elements connected between at least some of said studs whereby an electrical circuit similar to that of the diagram on the template is formed, and means electrically connected to said circuit for energizing the circuit.

2. Portable electrical educational apparatus of the character disclosed comprising, in combination, thin rectangular frame means having a substantially flat upper face member composed of non-conducting material, a plurality of studs of conducting material affixed to said face member in equally spaced parallel rows, the distance between studs in a row being the same as the distance between rows, a plurality of washers for said plurality of studs respectively, a template removably mounted upon said face member, said template having a plurality of openings therein corresponding in spacing to the disposition of the studs on said face member, said template being composed of non-conducting material, said openings being substantially similar in diameter to the washers whereby said washers snugly fit in said openings respectively and the template is prevented from substantial sliding movement on said face member, said template having means thereon forming an electrical circuit diagram, a plurality of circuit elements connected between at least some of said studs whereby an electrical circuit similar to that of the diagram on the template is formed, means electrically connected to said circuit for energizing the circuit, and meter means mounted upon said face member and having a pair of flexible connectors adapted to be detachably connected to selected pairs of said studs to measure the circuit characteristics at selected points therein.

LUIS DE FLOREZ.
